UNITED STATES PATENT OFFICE.

WILLIE ELDEN PEABODY, OF ESSEX, CONNECTICUT.

DESIGN FOR A GLOVE-HOLDER.

SPECIFICATION forming part of Design No. 25,538, dated May 19, 1896.

Application filed April 29, 1896. Serial No. 588,187. Term of patent 7 years.

To all whom it may concern:

Be it known that I, WILLIE ELDEN PEABODY, a citizen of the United States of America, residing at Essex, in the county of Middlesex and State of Connecticut, have invented and produced a new and original Design for Glove-Holders, of which the following is a specification, reference being had to the accompanying drawings, in which—

Figure 1 is a view of the embodied design as a whole. Fig. 2 is a view of the material of which it is composed in cross-section, scale enlarged.

The shape of the material is round, as shown in cross-section. The shape of the form as a whole conforms in general to the shape of the human hand and wrist.

What I claim is—

The design for a glove-holder substantially as shown and described.

WILLIE ELDEN PEABODY.
